UNITED STATES PATENT OFFICE

110,050

DESIGN FOR A WINTERFRONT FOR AUTOMOBILES

Willard L. Morrison, Lake Forest, Ill.

Application August 10, 1936, Serial No. 64,326

Term of patent 3½ years

To whom it may concern:

Be it known that I, Willard L. Morrison, a citizen of the United States, residing at Lake Forest, in the county of Lake and State of Illinois, have invented a new, original, and ornamental Design for a Winterfront for Automobiles, of which the following is a specification, reference being had to the accompanying drawing, forming part thereof.

Fig. 1 is a perspective view of the winterfront, showing the appearance of the winterfront with the shutters in open position.

Fig. 2 is a front view of the device.

Fig. 3 is a side view of the device.

Fig. 4 is a sectional view taken on the line 4—4 of Fig. 3.

The shutter elements are attached to the winterfront and constitute a part of the complete article.

The dominant or characteristic features of the present design are indicated in solid lines in the drawing.

I claim:

The ornamental design for a winterfront for automobiles substantially as shown and described.

WILLARD L. MORRISON.
